W. H. MINER, INC., A CORPORATION OF DELAWARE.

SIDE BEARING.

Application filed January 18, 1924. Serial No. 686,950.

This invention relates to improvements in side bearings.

One object of this invention is to provide a side bearing particularly adapted for use on railway cars and wherein the anti-friction element is automatically centered under the influence of gravity after each actuation thereof when the pressure is removed therefrom.

10 More specifically, an object of this invention is to provide a side bearing having counter weights so arranged that when the anti-friction element is moved to either side of its central normal position, the counterweights will be tilted and thereby moved to a position of unstable equilibrium to automatically insure the return of the anti-friction element when the load is removed.

20 In the drawing, forming a part of this specification, Figure 1 is a vertical sectional view taken through the ends of the body and truck bolsters of a car, showing my improvements in connection therewith. And Figure 2 is a vertical sectional view corresponding substantially to the line 2—2 of Figure 1.

25 In said drawing, 10 indicates the upper portion of the truck bolster, and 11 the underside of the opposed body bolster of a railway car. As shown, the improved bearing is attached to the truck bolster and comprises, broadly, a retaining or housing casting A; an anti-friction element B; and a pair of counterweights C.

30 The housing or retainer A is preferably in the form of a hollow box casting open at its top and bottom, having side walls 12 with laterally offset guides 121 therein and end walls 13. Lugs 14 are provided adjacent the bottom of the retaining member to receive rivets 15 or other fastening means whereby the housing may be secured to the bolster 10. A bearing plate 16, preferably having a hardened wearing portion 16', is secured in the bottom of the housing by rivets 17.

35 The anti-friction element comprises a central cylindrical roller portion 19 whose length is slightly less than the distance between the opposed edges 18 of the side walls 12, said roller having substantially triangular projections 20 at the ends thereof, and a pair of lugs 21 projecting longitudinally of the roller at the opposite ends of the lower edges of each triangular portion 20 as shown. It will be noted that the projecting portions

20 and 21 of the anti-friction element overhang the bearing portion 16' and prevent withdrawal of the anti-friction element through the top of the retaining member. The projections 20 are primarily to strengthen the lugs 21 and prevent their breaking and they also act as counterweights to assist the return of the roller to its normal central position after the load is released.

40 The main counterweights C are of like construction, the same being located one at each end of the anti-friction element. Each of said counterweights preferably rests on the bolster 10 and is in the form of a relatively thick plate having rounded corners 22 at the ends of the lower edge thereof, and of such size that they may be tilted about one of their rounded corners when the anti-friction element is shifted to either side of its normal central position. The counterweights are provided with vertically extending, elongated slots or openings 23 to loosely receive the lugs 21 as shown, and be engaged thereby. Openings 24 may be provided in the lower edges of the counterweights to permit foreign matter to be washed from within the housing, the side walls of the latter being similarly apertured as indicated at 25.

45 When the anti-friction element is shifted to either side of its normal central position, as for instance, to the left as shown in dotted lines in Figure 1, one set of the lugs 21 will lift or tilt the corresponding ends of the counterweights C, rocking them about their remote rounded corners 22. The parts will be in unstable equilibrium and as soon as the pressure or load is released from the anti-friction element, the counterweights C, acting together with the roller extensions 20, will automatically return the anti-friction element, under the influence of gravity, to its normal central position.

50 The guides are shaped to conform to the lines generated by the counterweights C during their tilting movements while actuated during the rolling movement of the anti-friction element, so that bodily shifting of the counterweights and the roller connected thereto with respect to the retaining member is practically prevented.

55 Oscillation of the anti-friction element when not under load is prevented to any appreciable extent, because the counter-

weights must be lifted at one end when said element rolls. Hence the roller will always be able to travel its full distance under load.

All of the parts are held in their assembled relation in the manner hereinbefore described, and automatic return of the anti-friction element to its normal central position is insured, without the necessity of using springs or other delicate means that are likely to get out of order. The arrangement is simple and the parts inexpensive and of rugged and substantial construction.

I have herein shown and described what I now consider the preferred manner of carrying out my invention but the same is merely illustrative, and I contemplate all changes and modifications that come within the scope of the claims appended hereto.

I claim:

20. 1. In a side bearing, the combination with a retaining member adapted to be secured to a truck bolster and having a bottom bearing surface; of an anti-friction roller having projections at its ends overhanging said bearing surface, each projection having a pair of lugs projecting at the lower edge thereof; and a pair of counterweights provided with vertical, elongated openings therethrough to loosely receive said lugs and be engaged thereby, whereby the weights are tilted about one end when the roller moves to either side of its normal central position and act to center said roller after the load is removed therefrom.
35. 2. In an anti-friction bearing, the combination with a housing having a bearing surface at its bottom and guides at its sides; of an anti-friction roller adapted to roll to either side of central position on said bearing surface between said guides and having projections at its ends overhanging said bearing surface to coact with said guides to retain the roller in the housing, each projection provided with a pair of lugs at the ends of the lower edge thereof and projecting longitudinally of the roller; and a pair of counterweights in said guides, each resting on said pair of lugs, whereby when the roller rolls to one side of central position, the weights are tiltably lifted at one end by the corresponding lugs at the ends of the roller and automatically return the roller to central position when the load is released therefrom.
50. 3. In a side bearing, the combination with a retaining member adapted to be secured to a truck bolster and having a bottom bearing surface; of a single anti-friction roller accommodated within said retaining member, said roller having a pair of projecting lugs at one end of the roller adjacent the lower edge; and a counterweight provided with

normally vertically disposed elongated openings therethrough to loosely receive said lugs, said lugs being adapted to engage said counterweight, whereby the same is tilted about one end portion when the roller moves to either side of its normal central position, said counterweight operating to center said roller after the load is removed therefrom.

4. In an anti-friction bearing, the combination with a mounting; an anti-friction element arranged to move to either side of central position with respect to said mounting; an elongated counterweight normally supported by said mounting; means connecting said counterweight and said anti-friction element, said means including anchoring members on said element eccentric to said element, having a lost motion connection with the counterweight; and means for limiting movement of said counterweight substantially to swinging movement about an end portion thereof.

5. In an anti-friction bearing, the combination with a mounting; of an anti-friction element movable to different positions on said mounting; a counterweight; means associated with said anti-friction element and said counterweight, and arranged to cause lifting of one end of said counterweight while the opposite end of said counterweight is restrained to swinging movement about a point, during movement of said anti-friction element in the direction of said opposite end of the counterweight, said action being reversed upon movement of the anti-friction element in the opposite direction.

6. In an anti-friction bearing, the combination with a retainer having side and end walls, and guide recesses in said side walls; of an anti-friction element arranged in said retainer and provided with a plurality of eccentric projections; and counterweights of elongated formation arranged to swing about the opposite end portions in said guide recesses and limited against longitudinal movement with respect to the retainer by the walls of said recess, each of said counterweights being provided with spaced elongated slots extending normally in a vertical direction and adapted for the reception of said eccentric projections of said anti-friction element only, whereby movement of said anti-friction element to either side of central position tilts said counterweights about one end portion of each of the same, said projections operating in said slots serving to prevent shifting of said roller without rotation thereof.

In witness that I claim the foregoing I have hereunto subscribed my name this 14th day of January, 1924.

STACY B. HASELTINE.
